C. PFANSCHMIDT.
PAPER SERVER FOR BARBERS' CHAIRS.
APPLICATION FILED SEPT. 29, 1908.

936,030.

Patented Oct. 5, 1909.

UNITED STATES PATENT OFFICE.

CHARLES PFANSCHMIDT, OF CHICAGO, ILLINOIS, ASSIGNOR TO THEO. A. KOCHS COMPANY, OF CHICAGO, ILLINOIS, A CORPORATION OF ILLINOIS.

PAPER-SERVER FOR BARBERS' CHAIRS.

936,030.

Specification of Letters Patent.

Patented Oct. 5, 1909.

Application filed September 29, 1908. Serial No. 455,384.

To all whom it may concern:

Be it known that I, CHARLES PFANSCHMIDT, a citizen of the United States, residing at Chicago, in the county of Cook and State 5 of Illinois, have invented certain new and useful Improvements in Paper-Servers for Barbers' Chairs, of which the following is a specification.

In order to promote sanitary conditions, 10 the head rest of a barber's chair is frequently provided with mechanism for permitting a strip of paper to be fed across the head rest and torn off from time to time so that each occupant of the chair may be provided with 15 a fresh strip of paper. Mechanism of this character ordinarily comprises a holder for a roll of paper located on one side of the head rest and the cutter for the paper located on the other side, which arrangement of the 20 parts permits the paper to be drawn from the roll and across the head rest and severed by the cutter from time to time as occasion may require.

The object of the present invention is 25 to improve the construction and arrangement of the paper holder, whereby a roll of paper may be easily and quickly slipped into place, and to improve the construction and arrangement of the cutter in such manner as 30 to permit quick and ready manipulation of the same by the barber.

In certain previous constructions, it has 35 been necessary to manipulate the cutter with one hand and draw out the paper with the other, which is an awkward and unsatisfactory method of performing the operation. The cutter of the present invention is so arranged and constructed that these two operations may be performed with one hand and 40 in a very easy manner; at the same time the cutter is so formed and constructed that it will hold and clamp the paper firmly in position, when desired, thereby preventing displacement of the paper by movements of the 45 head of the occupant of the chair.

Further objects will appear in the detailed 50 description of the invention, which consists in the features of construction and combination of parts hereinafter described and claimed.

In the drawings, Figure 1 is a sectional 55 view of the paper holding cylinder and cutter, showing the method of feeding the paper over the head rest; Fig. 2 a cross sectional view of the paper cylinder; Fig. 3 a

cross sectional view of the end cap for the cylinder; Figs. 4 and 5 fragmentary side elevations of opposite sides of the cylinder; Fig. 6 a plan view of the serrated cutting plate; Fig. 7 a longitudinal sectional view of 60 the cutter; and Fig. 8 an enlarged end elevation of the same.

As shown in the drawings, the paper holding cylinder 9 is located at the front side of and below the head rest 10, and the cutter 11 is similarly located at the rear side of the head rest. The paper holding cylinder comprises a body portion 12 of split cylindrical formation, having a slot 13 extending from end to end of the body portion. 70 One edge of the slot is outwardly turned to form a rounded lip 14 over which the paper is fed. The lip, at each end, is provided with a backwardly turned flange 15, which flanges are in register with studs 16 formed 75 on the opposite side of the body of the cylinder by outwardly pressing the metal at the intended points. The ends of the cylinder are closed by means of caps 17, in the form shown in Fig. 3, each of which comprises an end wall 18 which is connected with a flange 19, the wall 18 being inwardly depressed, as regards the flange, to provide an annular groove or channel 20 around the inner or connected edge of the flange. The flange is 80 provided, on opposite sides, with T slots 21, which slots are intended to register with the studs 16 and the flanges 15, respectively, so that when the parts are assembled the end edges of the body portion of the cylinder 90 will be entered into the grooves or channels 20 and held therein by the locking action of the studs 16 and the flanges 15, when the caps are turned to bring the T slots into position to engage such projections. The cylinder, as a whole, is supported from the head rest by means of brackets 22.

The cutter 11 comprises a casing 23 of boxlike formation, having a top wall 24, a bottom wall 25, and an inner cross wall 100 26, the front side of the casing being open; and the casing is closed, at its ends, by end walls 27. The casing co-operates with a cutter plate 28 which is provided, at its ends, with inwardly extending ears 29 which are 105 of suitable length to hold the upper portion of the cutter plate out of contact with the forward edge of the top of the casing, leaving a slot or opening 30 for the discharge therethrough of the paper. The cutter plate 110

is provided, along its lower or free edge, with teeth 31 which engage and sever the paper in a manner to be hereinafter described. The serrated or toothed edge of 5 the cutter projects a considerable distance beyond and below the lower wall 25 of the casing, which wall, along its front edge, is provided with a plurality of forwardly extending lugs 32 which register with and en- 10 ter a plurality of slots 33 arranged in line with the cutter plate. The ears 29 are hinged to the casing by means of a pivot rod 34 which passes through the end walls of the casing and extends from end to end 15 thereof. In order to hold the cutter plate normally in position to bring the slots 33 into register with the lugs 32, a coiled spring 35 is provided, the ends of which engage the cutter plate and casing in such manner as 20 to hold them in normal position with respect to one another.

In use, a roll of paper can be entered into the paper holding cylinder by removing one of the caps, which removal is effected by 25 turning the cap into position to bring the projections on the body of the cylinder into alignment with the stems of the slots. When the paper is positioned, its ends will abut against the inwardly projecting center 30 portions of the end caps in such manner as to properly position and center the paper with respect to the slot through which it is fed. The end of the paper will then be drawn up over the head rest and passed 35 through the upper slot 30 of the cutter, and thence down in front of the lugs. This position of the paper can be effected by swinging the cutter plate against the tension of the spring, away from its closed or clamp- 40 ing position into the position shown in dotted lines in Fig. 1. Upon its release, the cutter plate will swing back into normal position, thereby causing the lugs 32 to force the paper into the slots 33 in such manner 45 as to tightly clamp the paper and prevent its retraction. When it is desired to pull out a soiled section of paper, this operation can be performed with one hand, by inserting the fingers behind the projecting end of 50 the sheet of paper which lies behind the serrated edge of the cutter, and thereafter slightly lifting the cutter by a pressure of the fingers and simultaneously drawing out the paper sufficiently to permit a firm hold 55 of the paper to be secured between the thumb and finger. Thereafter the tension of the

paper, as it is drawn out, will be doubled to raise the cutter plate sufficiently to un-clamp the paper and permit its withdrawal. After a sufficient length of paper has been 60 drawn out in the manner above noted, it can be torn off by a tearing movement across the serrated edge of the knife. By projecting the edge of the knife a considerable distance beyond the edge of the frame, a sufficient length of paper is allowed to project from the frame to permit of easy manipulation with the fingers; and by forming the clamp for the paper in the manner specified additional manipulation of the device is 65 unnecessary.

The device, as a whole, is one which is adapted to fit the head rest of any standard formation, and the manner in which the mechanism is operated permits the manipulation with one hand, which is frequently very desirable, since the other hand of the barber may be otherwise engaged at the time when it is desired to shift the paper.

What I regard as new and desire to secure 80 by Letters Patent is:

1. In a severer of the class described, a paper holder of cylindrical formation, comprising a split body portion, one of the edges of said body portion being turned back to 85 form a rounded lip having rearwardly extending flanges at its ends, and caps closing the ends of said cylinder and having flanges provided with slots adapted to be engaged by the first mentioned flanges when the caps 90 are turned to locked position, substantially as described.

2. In a severer of the class described, a paper holder of cylindrical formation comprising a split body portion having one of 95 its edges outwardly turned to form a rounded lip provided, at its ends, with locking flanges, studs formed on the body portion directly opposite the locking flanges, and a pair of caps, each comprising a body portion 100 and having a rim or flange connected therewith in a manner to afford annular grooves or channels for the reception of the ends of the body portion, said arms or flanges being further provided, on opposite sides, with 105 slots adapted to engage respectively the locking flanges and the studs, substantially as described.
